UNITED STATES PATENT OFFICE.

MATTHEW SMITH MOORE, OF LONDON, ENGLAND, ASSIGNOR TO COWLISHAW WALKER & COMPANY (1920) LIMITED, OF LONDON, ENGLAND.

COAL CUTTING AND SIMILAR MACHINE.

Application filed May 6, 1922. Serial No. 559,062.

To all whom it may concern:

Be it known that I, MATTHEW SMITH MOORE, a subject of the King of Great Britain and Ireland, residing at 14/16 Cockspur Street, London, S. W. 1, England, have invented certain new and useful Improvements Relating to Coal Cutting and Similar Machines, of which the following is a specification.

10 This invention relates to coal cutting and similar machines of the kind in which the body of the machine is mounted upon supports capable of adjustment for the purpose of tilting the body of the machine to any 15 convenient desired degree laterally or longitudinally or both laterally, in either direction, and longitudinally.

Such machines have before been proposed in which the body of the machine is supported 20 at the cutter end on two adjustable supports disposed laterally with reference to the longitudinal axis of the body of the machine, and at the haulage end by a single and centrally disposed support.

25 Now the present invention has among its objects so to provide the supports that their adjustment for tilting the body of the machine laterally or longitudinally may be effected at the haulage end of the machine.

30 The invention is illustrated in the accompanying drawings in which

Figure 1 is a diagrammatic plan of a coal cutting machine illustrating the present invention.

35 Figure 2 is a diagrammatic view of one of the adjustable lateral supports mounted at the haulage end of the machine.

Figure 3 is a similar diagrammatic view of one of the lateral supports shown in the invention 40 inclined position corresponding to the position assumed by the body of the machine after an adjustment has been made and illustrating the manner in which the rigidity of the machine body is ensured.

45 Figure 4 shows a detail sectional elevation of a coal cutting machine, the section being taken on the line $z-z$ of Fig. 5, and

Figure 5 is a detail plan corresponding to Figure 4.

50 Thus according to the invention the machine body a is mounted upon two laterally disposed and adjustable supports b at the haulage end of the machine, and is provided with a reduced portion a' disposed within 55 a centrally disposed support c at the cutter

end of the machine that is not vertically adjustable, in such a manner that the lateral or longitudinal tilting of the body of the machine effected by the adjustment of the supports at the haulage end may be rotatably 60 freely effected, this being most conveniently done by mounting the cutter end of the machine within the support or ring c concentric with the longitudinal axis $x-x$ of the body, and by mounting this ring upon horizontally 65 disposed trunnions $d d$ carried within laterally disposed stationary brackets $e e$ which may be secured to the usual longitudinal frame supporting members m , so that thus while the body a of the machine is capable 70 of rotation to the extent desired in one or other direction on its longitudinal axis $x-x$, it is capable of being tilted on the transverse axis $y-y$ of the trunnions $d d$ as required according to the adjustments made of 75 the supports b at the haulage end of the machine.

The invention has also among its objects to provide simple means to ensure the rigidity of the machine body a , and its freedom from 80 any disposition to sway on any variation in the adjustment of the laterally disposed supports b at the haulage end of the machine, which results in a variation in the inclination or position of the respective supports. For 85 this purpose according to the invention the lateral supports b at the haulage end of the machine are each provided of two parts $b^1 b^2$, one b^2 being a central part screw threaded upon its exterior, and the other b^1 being of a corresponding tubular form 90 screw threaded upon its interior, the central part b^2 being thus adapted to be screwed within the tubular part b^1 so that the effective length of the support b thus constituted 95 is capable of variation on the rotation of one part with reference to the other. For this purpose one of the parts of the support, conveniently the tubular part b^1 , has mounted upon it, or integrally formed with it, in 100 a convenient position in its length, a worm wheel f which is adapted to engage with a worm g whose axis is disposed at an angle to that of the worm wheel f , so that thus the spindle h upon which the worm g is 105 mounted may be directed outwardly to the respective sides of the machine as indicated in Figure 4, in a position convenient for rotation by the machine operator at the haulage end, by means of hand levers or wheels. 110

According to the invention, with a view to ensure the rigidity of the position of the machine body in any position in which it may be tilted upon its longitudinal axis, I mount 5 the one part of one of the lateral supports at the haulage end, conveniently the tubular part b^1 , within a guide or guiding boss i mounted upon the machine body a . The slot or hole within the guide or guiding 10 boss i is so provided as to permit any desired degree of tilting of the machine body about the transverse axis $y-y$ of the trunnions $d d$ at the cutter end of the machine, but for any lateral tilting of the machine body about 15 the longitudinal axis $x-x$, the guide or guiding boss i affords a positive but a sliding connection between the support b and the machine body a , so that thus, while each of the lateral supports b at the haulage end 20 of the machine is independently adjustable, the haulage end of the machine is rigidly supported as usual on the longitudinal frame supporting members m notwithstanding inequality in the adjusted height of the sup- 25 ports.

It follows that inasmuch as the respective lateral supports b at the haulage end of the machine are adapted for the variation of their height or length and position in the 30 manner described, their respective ends are so formed and mounted as to permit of this. Thus the respective ends of the adjustable lateral supports b at the haulage end of the machine are provided with 35 spherical heads $k l$ and they are engaged within oppositely disposed bearings provided with caps $k^1 l^1$ adapted positively to retain the spherical ends within the bearings, while permitting of variation of position of the support. It will be understood 40 that the bearings for the upper spherical heads k are provided in the body a of the machine while the bearings for the lower spherical heads l are provided within base 45 blocks l^2 secured upon the longitudinal frame supporting members m , the base blocks protruding through holes or apertures n provided in the lower or base part of the machine body.

50 In the construction illustrated in Figure 4 it will be understood that the upper end of the outer part b^1 of the support is adapted for the reception of a stem k^2 integrally provided with the head k and that the stem k^2 is firmly fixed within the part b^1 of the support, and that similarly the central part b^2 of the support is integrally provided with the head l . Means may be provided as illustrated in Figure 4 for the lubrication of the 55 screw threads. Such means may consist of an axial hole b^3 extending through the head k and stem k^2 . Holes in corresponding position are provided in the machine body which are capable of being closed by means of a 60 plug such as a^2 .

The tubular and central parts $b^1 b^2$ of the support b at their respective outer ends are thus provided with spherical heads in the manner described, and the worm wheel f is advantageously provided on the tubular 70 part of the respective lateral supports near the upper end thereof, so that thus the tubular support is adapted to slide within the guide or guiding boss i on the machine body.

It will be understood that the invention 75 comprises the constructional features which are herein specifically described.

The manner of mounting the machine body a at the cutter end of the machine may vary considerably, but the position of this 80 support is so disposed that the necessary extent of vertical adjustment at the cutter end of the machine may be effected in the manner described by the adjustment of the lateral supports b at the haulage end of the 85 machine, and by the body of the machine being tilted upon the transverse axis $y-y$. This is conveniently effected in the manner hereinbefore specifically described by carrying the machine body a near the cutter 90 end within the ring c concentric with the longitudinal axis $x-x$ of the machine in such manner as to permit partial rotation of the machine body a within the ring c , and by providing this ring with trunnions $d d$ 95 in opposite positions, so that the ring may thus be carried in bearings at each side through which the trunnions pass. The trunnions may be mounted advantageously beneath the longitudinal axis $x-x$ of the 100 machine body, or even above the longitudinal axis, or yet again the body of the machine may be mounted near the cutter end in any other manner than herein specifically indicated, whereby the body at the cutter 105 end may be partially rotated or tilted on its longitudinal axis and also tilted on the axis of the trunnions, without however using adjustable lateral supports at the cutter end 110 of the machine.

It will, however, be understood that the invention is not limited to the constructional features hereinbefore described. The adjustable lateral supports at the haulage end of the machine may for example be constructed so as to be adjustable in any other manner than described, and one or other of the adjustable lateral supports may be held in the manner described so that the body of the machine may be rigidly held no 120 matter what the extent of adjustment may be of the respective lateral supports.

I claim:

1. A coal cutting machine comprising a 125 body, a central support, adjustable supports at the haulage end of the machine comprising telescoping screw threaded members having spherical end members, a base for the body, and sockets on the base and body for receiving the said spherical end members to 130

permit partial rotation of the body both longitudinally and transversely of the central support, and means for extending and contracting the telescopic members.

5. 2. A coal cutting machine comprising a body, a central support therefor, adjustable supports at the haulage end of the machine comprising telescopic threaded tubes, a worm wheel on the outer tube, a worm en-
10 gaging the worm wheel to impart rotary motion thereto and to the tubular member to extend or contract the same, plugs carried in the end of each tubular member and having spherical heads, sockets for the said heads permitting partial rotation of the body both longitudinally and transversely
15 of the central support, and means for rotating the worm.

3. A coal cutting machine comprising a body, a pivoted ring at the center of the machine having the body rotatably supported therein to permit the body to swing about its longitudinal and transverse axes, adjustable supports at the haulage end of the ma-
20 chine comprising extensible telescoping members, and means for extending or contracting the adjustable supports to impart said movement to the body.

4. A coal cutting machine comprising a

body, a pivoted ring at the center of the ma-
chine having the body rotatably supported therein for pivotal movement about its longitudinal and transverse axes, adjustable supports on each side of the machine at the haulage end comprising telescoping screw 30 threaded, tubular members, plugs having spherical heads within one end of each tube, bearings for the said heads to permit swinging movement of the supports, a guiding boss secured to the body, and encircling the 35 adjustable support to rigidly support the body in its adjusted position, means for adjusting the supports to impart said movement to the body, and means for lubricating the same.

5. A coal cutting machine comprising a body, cutting means at one end and haulage means at the other end thereof, skids beneath both sides of the body, a central ring having the body mounted therein for movement about its longitudinal axis, means at the haulage end of the machine for imparting the said movement to the body, the cutting means capable of being swung laterally 50 in a horizontal plane to extend over either 55 of the skids.

MATTHEW SMITH MOORE.
